UNITED STATES PATENT OFFICE.

CHARLES B. SHEPHERD, OF SPRINGFIELD, MASSACHUSETTS, ASSIGNOR TO WILLARD REID, OF SCARSDALE, NEW YORK.

RAIL ANCHOR.

Application filed July 19, 1928. Serial No. 293,918.

This invention relates to those devices designed to prevent the longitudinal creeping of rails and known as rail anchors.

This invention has for an object a one-piece rail anchor which is efficient in use and easy to apply and remove, if necessary.

Another object of this invention is to provide a rail anchor the normal length of which is greater than the width or cross-section of the rail base flange which it is intended to engage.

A further object of this invention is to provide a rail anchor having clamping means, said clamping means being resilient and yielding.

An additional object of this invention is to provide a rail anchor having a clamping member which includes a yielding and resilient S-shaped, three-fold or three-ply member adapted to engage the lower surface of the rail base flange.

A still further object of this invention is to provide a rail anchor which, when in position on a rail base flange and tilted under sufficient pressure, causes various parts thereof to contact and brace each other, increasing the rigidity of the anchor and resulting in a firm powerful biting action on the rail base flange by the anchor.

Additional objects will appear from the following description, hereinafter appended claims and the accompanying drawings in which:

Figure 1 is an isometric view of the anchor constituting this invention.

Figure 2 illustrates the anchor constituting this invention applied in position on the rail base flange, the rail base flange being shown in section.

Figure 3 illustrates one of the positions assumed by the anchor during application to a rail base flange.

Figure 4 illustrates the relation of parts before and after the anchor has been applied to the rail base flange, the dotted lines illustrating the anchor after application and the full lines illustrating the anchor prior to application.

Figure 5 illustrates a modification of the anchor illustrated in Figures 1 to 4 inclusive.

Figure 6 illustrates another modification.

Referring to the drawings and especially to Figures 1 to 4 inclusive, in which one modification of my invention is illustrated, the reference numeral 1 designates a body member

adapted to extend transversely beneath the rail base flange. The body member 1, at one end thereof, is formed with a rail flange-engaging means, preferably comprising an upstanding lip 2, the inner surface 3 of which is adapted to engage a vertical edge of a rail base flange. The opposite end of the body member 1 is formed with an S-shaped, three-fold or three-ply loop member 4. The lower end 5 of the S-shaped member 4 is curved and constitutes a tie-abutting means. Connected to the tie-abutting means 5 by means of an easy bend 6 is a substantially vertical shank 7 which terminates in a substantially rigid member 8 bent at an angle to said shank 7, and adapted to engage the upper surface of a rail base flange.

The member 8 is adapted to engage the upper surface of a rail base flange and may be made of any form or configuration. In the drawings I have illustrated it as having an angle corresponding to the angle of the rail base flange which it is intended to engage.

The apex or upper surface 9 of the S-shaped member 4 is disposed beneath the member 8 a distance normally less than the cross-section or thickness of the rail base flange adapted to be engaged thereby, and, together with the substantially rigid member 8, constitutes means to clamp and grip a rail base flange.

Normally the face 10 of the S-shaped member is positioned adjacent but spaced from the inner surface 6' of the easy bend 6. The upper end 11 of the S-shaped member 4 is in close proximity to a point 12 of the middle or second ply or fold of the S-shaped member. If desired, the anchor may be so constructed that these two points contact. The horizontal distance between the inner face 3 of the lip 2 and the face 10 of the S-shaped member 4 is normally the same as or greater than the width of a standard rail base flange. Also, the distance between the inner face 3 of the lip 2 and the inner face of the shank 7 is greater than the width of a standard rail base flange.

The grip of the anchor depends on the distortion of the various parts of the anchor from their normal position to their position on a rail base flange. In the anchor constituting this invention the degree of distortion depends on the distance between the clamping elements 8 and 9 and the plane occupied by the portion 13 adjacent the lip member 2. As

above described, the distance between the clamping elements 8 and 9 is normally less than the thickness of a rail base flange to be engaged thereby.

- 5 The portion or surface 13 adjacent the lip 2 is made to lie in the same plane or in a plane higher than that occupied by the apex 9, whereby, when applied to the rail base flange, sufficient distortion is obtained to effect a firm grip by the anchor. If desired, the member 8 may be spaced from the apex 9 a distance greater than the thickness of the rail base flange to be engaged thereby. If the anchor is so constructed, the portion 13 is 10 made to occupy a plane much higher than that occupied by the apex 9 in order that the anchor may be distorted sufficiently to attain a firm gripping action. Thus, by proper relation of these parts any desired grip or holding force may be obtained.

20 In application the clamping means 8 and 9 of the anchor are applied to the rail base flange and pushed on as far as they will go. At the end of this operation the anchor will 25 assume the position illustrated in Figure 3. The end 14 of the member 8 will bear upon the upper surface of the rail base flange and the lip member 2 will be beneath and engage some point on the under surface of the rail 30 base flange. Pressure is then applied to the anchor, as by striking the outer face 15 of the vertical shank with a spike-maul, whereby the anchor is distorted and the parts 8 and 9 caused to travel upon the rail base flange until the lip 2 clears the opposite vertical edge 35 of the rail base flange and snaps into position.

35 In the application of the anchor to the rail base flange, the substantially rigid member 8 and the shank 7 are forced upwardly and outwardly, the easy bend 6 serving as a fulcrum as shown in Figure 4. At the same time the S-shaped member 4 is depressed, whereby the face 10 of the S-shaped member 4 is moved downwardly and outwardly. During 40 this depression the face 10 may or may not contact with the inner face 6' of the easy bend 6.

45 Also, if sufficient distortion occurs, the upper end 11 of the S-shaped member 4 may contact with the middle fold at the point 12. Due to this distortion, the applied pressure forces the end 14 of the member 8 to travel up on the inclined surface of the rail base flange, and the apex 9 to travel transversely 50 on the under surface of the rail base flange until the lip 2 clears the opposite edge of the rail base flange and snaps into position.

55 At the beginning of the application of the anchor to the rail base flange, due to the raising of the substantially rigid member 8, its angle is changed. During the application the end 14 rides upon the inclined surface of the rail base flange and when the anchor snaps into position the angle of the mem-

ber 8 is again changed and it assumes an angle approximating the angle of the rail base flange. Throughout the application of the anchor to the rail base flange the body member 1 does not substantially yield or flex. The yielding is substantially confined within the clamping means 8 and 9 and its cooperating parts, namely, the shank 7 and the easy bend 6.

60 In applying the anchor it is possible to overdrive the anchor and force the inner surface of the shank 7 in contact with the vertical edge of the rail base flange. This, however, cannot occur until after the lip 2 has cleared the opposite edge of the rail base flange. If the anchor is overdriven to any extent, the inner face 3 of the lip 2 will be spaced from the vertical edge of the rail base flange, which it is intended to engage, a distance equal to the amount that the anchor has been overdriven. As soon as any pressure or force is applied to the tie-abutting portion 5, which will occur when the rail starts to creep or slip, the anchor will adjust itself by shifting transversely of the rail and assuming its normal applied position.

65 The normal position of the anchor on a rail base flange is illustrated in Figure 2. It will be seen that the rail is engaged and tightly held between the clamping means formed by the member 8 and the apex 9 of the S-shaped member 4. The vertical edge of the rail base flange within the clamping means 8 and 9 is free and spaced from the shank 7. Also, a portion of the under surface adjacent the vertical edge of the rail base flange is free and 70 spaced from the S-shaped member 4. The opposite edge of the rail base flange is engaged by the inner surface 3 of the upstanding lip 2. Due to the disposition of the portion 13 and the distance between the elements 8 and 9, the necessary upward and downward pressures to secure a firm grip are obtained. The vertical edge-engaging means 3 serves as a stop preventing the anchor from being forced off the rail and helps to sustain the 75 clamping action exerted by the members 8 and 9.

80 In operation, when pressure is brought to bear against the tie-abutting means 5, the anchor may assume a diagonal position on the rail and the opposite edges of the face 3 and inner face of the shank 7 may contact against the rail edges.

85 Further application of pressure causes the anchor to tilt and produces a vertical pull on the shank 7 and a pressure on the apex 9. Since the member 8 is substantially rigid and does not yield appreciably, the surface 10 under sufficient pressure will be forced into contact with the face 6', thus forming a brace and restricting further tilting. In the tilted position the upper rail base flange-engaging means 8, and the lower rail flange-engaging

means 9 will bite into the rail base flange and effectively restrain any further slipping or movement on the part of the rail.

The modification illustrated in Figure 5 differs from the preferred form illustrated in Figures 1 to 4 inclusive, in that the shank 7' is substantially at right angles to the tie-abutting means 5'. It further differs from the preferred modification in that the outer surface 10' of the S-shaped member 4' does not cooperate with any easy bend to form a brace during tilting of the anchor. The face 10' may, however, under sufficient pressure contact with the shank 7'. In all other respects this modification is similar to the preferred form and further description thereof is deemed unnecessary.

The modification illustrated in Figure 6 differs from the preferred form illustrated in Figures 1 to 4 inclusive in that the S-shaped member 44 has its middle member disposed at an angle instead of horizontally, whereby the upper portion 41 thereof cannot contact with the middle member 42. In all other respects this modification is similar to the preferred form and further description thereof is considered unnecessary.

I claim:

1. A rail anchor comprising a body member, rail flange-engaging means disposed on one end thereof, an S-shaped member disposed on the opposite end of said body member and adapted to engage the under surface of a rail base flange, and means to engage the upper surface of a rail base flange and cooperating with said S-shaped member to form a rail base flange-clamping means.

2. A rail anchor comprising a body member, rail flange-engaging means disposed on one end thereof, an S-shaped member adapted to yieldingly engage the under surface of a rail base flange, and means to engage the upper surface of a rail base flange cooperating with said S-shaped member to form a rail-clamping means.

3. A rail anchor comprising a body member, rail flange-engaging means disposed on one end thereof, an S-shaped member adapted to yieldingly engage the under surface of a rail base flange, and substantially rigid means to engage the upper surface of a rail base flange cooperating with said S-shaped member to form a rail-clamping means.

4. A rail anchor comprising a body member, rail flange-engaging means disposed at one end thereof, an S-shaped member disposed at the other end thereof, the apex of said S-shaped member being adapted to engage the under surface of a rail base flange, and means to engage the upper surface of a rail base flange and cooperating with said apex to form a rail base flange-clamping means.

5. A rail anchor comprising a body member, rail flange-engaging means disposed at

one end thereof, an S-shaped member disposed at the other end thereof, the apex of said S-shaped member being adapted to engage the under surface of a rail base flange, and means to engage the upper surface of a rail base flange and cooperating with said apex to form a rail base flange-clamping means, the surface adjacent the first named rail flange-engaging means and said apex lying in planes higher than that occupied by said body member.

6. A rail anchor comprising a body member, rail flange-engaging means disposed at one end thereof, an S-shaped member disposed at the other end of said body member and adapted to engage the under surface of a rail base flange, said S-shaped member forming a tie-abutting means, a shank connected to said tie-abutting means, said shank terminating in a member adapted to engage the upper surface of a rail base flange and cooperating with said S-shaped member to form a rail base flange-clamping means.

7. A rail anchor comprising a body member, an S-shaped member disposed at one end thereof and adapted to engage the under surface of a rail base flange, a shank, a bend connecting said shank and said member disposed in close proximity to the second fold of said member, said shank terminating in means to engage the upper surface of a rail base flange and cooperating with said S-shaped member to form a rail base flange-clamping means and rail base flange-engaging means disposed on the opposite end of said body member.

8. A rail anchor comprising a body member, an S-shaped member disposed at one end thereof and adapted to engage the under surface of a rail base flange, a shank, a bend connecting said shank and said S-shaped member disposed in close proximity to the second fold of said S-shaped member, said shank terminating in means to engage the upper surface of a rail base flange and cooperating with said S-shaped member to form a rail base flange-clamping means, and rail base flange-engaging means disposed on the opposite end of said body member, the surface adjacent the rail flange-engaging means and the apex of said S-shaped member being disposed in planes higher than said body member.

9. A rail anchor comprising a body member, an S-shaped member disposed at one end thereof and adapted to engage the under surface of a rail base flange, a shank, a bend connecting said shank and said S-shaped member disposed in close proximity to the second fold of said S-shaped member, said shank terminating in substantially rigid means to engage the upper surface of a rail base flange and cooperating with said S-shaped member to form a rail base flange-clamping means, and rail base flange-engag-

ing means disposed on the opposite end of said body member.

10. A rail anchor comprising a body member, rail base flange-engaging means disposed on one end of said body member, an S-shaped member adapted to engage the under surface of a rail base flange disposed on the opposite end of said body member, a bend, a shank connected by said bend to said S-shaped member, said shank terminating in means to engage the upper surface of a rail base flange and cooperating with said S-shaped member to form a rail base flange-clamping means, said S-shaped member having its middle or 15 second fold in close proximity to said body member.

11. A rail anchor comprising a body member, rail base flange-engaging means disposed on one end of said body member, an S-shaped member adapted to engage the under surface of a rail base flange disposed on the opposite end of said body member, a bend, a shank connected by said bend to said S-shaped member, said shank terminating in 20 means to engage the upper surface of a rail base flange and cooperating with said S-shaped member to form a rail base flange-clamping means, said S-shaped member having its middle or second fold in close proximity to said body member and to said bend.

12. A rail anchor comprising a body member, rail flange-engaging means disposed on one end thereof, rail flange-clamping means disposed on the other end of said body member, said clamping means comprising means 35 to engage the upper surface of a rail flange, and an S-shaped member cooperating therewith to grip said rail flange.

13. A rail anchor comprising a body member, rail flange-engaging means disposed on one end thereof, rail flange-clamping means disposed on the other end of said body member, said clamping means comprising means 40 to engage the upper surface of a rail base flange, an S-shaped member cooperating therewith, and a shank connecting said means for engaging the upper surface of the rail base flange and said S-shaped member, whereby forces or stresses tending to distort either or both of said portions may be 45 communicated.

14. A rail anchor comprising a body member, rail flange-engaging means disposed at one end thereof, rail flange-clamping means disposed at the other end of said body member, said clamping means comprising means 50 to engage the upper surface of a rail base flange, an S-shaped member cooperating with said upper rail flange-engaging means, a

shank connecting said upper rail base flange-engaging means on said S-shaped member, said shank and said S-shaped member being disposed to yieldingly cooperate with said means for engaging the upper surface of said rail base flange.

15. A rail anchor comprising a body member, rail flange-engaging means disposed on one end thereof, an S-shaped member adapted to yieldingly engage the under surface of a rail base flange, means to engage the upper 70 surface of a rail base flange cooperating with said S-shaped member, and a yieldable shank connecting said S-shaped member and said means to engage the upper surface of the rail base flange.

16. A rail anchor comprising a body member, an S-shaped member disposed at one end thereof and adapted to engage the under surface of a rail base flange, a yieldable shank, a bend connecting said yieldable shank and said S-shaped member disposed in close proximity to the second fold of said S-shaped member, said yieldable shank terminating in substantially rigid means to engage the upper surface of a rail base flange and cooperating with said S-shaped member to form a rail base flange-clamping means, and rail base flange-engaging means disposed on the opposite end of said body member.

17. A rail anchor comprising a body member, rail flange-engaging means disposed on one end of said body member, an S-shaped member adapted to engage the under surface of a rail base flange disposed on the opposite end of said body member, a shank connected to said S-shaped member, said shank terminating in means to engage the upper surface of a rail base flange and cooperating with said S-shaped member to form a rail base flange-clamping means, said S-shaped member having a portion thereof in close proximity to said shank.

18. A rail anchor comprising a body member, rail flange-engaging means disposed on one end of said body member, an S-shaped member adapted to engage the under surface of a rail base flange disposed on the opposite end of said body member, a bend, a shank connected by said bend to said S-shaped member, said shank terminating in means to engage the upper surface of a rail base flange and cooperating with said S-shaped member to form a rail base flange-clamping means, said S-shaped member having a portion thereof in close proximity to said bend.

In testimony whereof, I have affixed my signature to this specification.

CHARLES B. SHEPHERD.
